UNITED STATES PATENT OFFICE.

EDNA SIBLEY TIPTON, OF NEW YORK, N. Y.

BEAUTY COMPACT.

Application filed December 24, 1926. Serial No. 156,812.

The object of this invention is to supply a small, compact and artistic case or container for a plurality of aids to facial beauty, such as face powder, rouge, mascara, 5 eye-shadow, lip-stick, an eye-brow brush, etc.

An illustration of one form of practical embodiment of my inventive idea, whereby the above stated object is attained is clearly shown in the accompanying drawings in 10 which—

Fig. 1 is a side elevation of the case.

Fig. 2 is a transverse section of said case intermediate the caps or end closures; with the various accessories removed.

Fig. 3 is an end view.

Fig. 4 is a central, vertical longitudinal section of the case, in the position shown in Fig. 1, and showing certain beauty aids in position within the case.

Fig. 5 is a side view of a small container for face powder, and indicating how said container is carried with a closure member.

Figs. 6 and 7 are a side and end view respectively of said powder container.

Fig. 8 is a side view of a lip-stick and an eye-brow pencil projecting from opposite ends of a tubular sleeve and showing said sleeve carried by a supplementary elongated tube, which in turn, is carried by a 30 closure element.

Fig. 9 shows said lip-stick and pencil removed from said tube.

Fig. 10 is a side view of a tubular container for paste, rouge and mascara showing said container as carried by a closure member.

Fig. 11 is an end view of the adjacent end of Fig. 10.

Fig. 12 is a perspective view of the container shown in Figs. 10 and 11, and in the open position.

Fig. 13 is a side view of an eye-brow brush in position for use.

Fig. 14 is a central, longitudinal section of the carrier for said brush showing the brush in its reversed position.

Fig. 15 is a side view of said brush removed from its carrying members.

It will be a material aid to a full understanding of the reasons for the construction shown in said drawings to here point out that the case proper, as shown in Fig. 1, together with the closure members for the respective ends of the tubes or barrels thereof, constitute the permanent and regular portions and members of this device; and

that the supplementary devices shown in Figs. 5 to 15 of the drawings constitute accessories which may be changed, interchanged and renewed at will, and as use and necessity may require; said devices, in and of themselves, as considered apart from the complete organization shown in Fig. 4, are termed re-fills, and in the commercial promotion of this invention are supplied and may be purchased as needed, although the compact is originally sold complete as in Fig. 4.

In detail the construction shown in said drawings is as follows:

Within the case 1 are mounted two barrels or tubular members 2 and 3 arranged in contiguous parallel relation. The ends of said barrels are open and each end is supplied with a closure member 4, 5, 6 and 7 respectively. Said closure members are also tubular in form, having an outside diameter of such size as to adapt them to fit closely into the ends of said tubes 2, 3 and to be readily insertable into and removable therefrom. All of said closure members are preferably identical in size and shape, and are of socket-like construction with their openings or sockets disposed inwardly when in their closed position within said barrels 2 and 3,—see Figs. 5, 8, 10 and 14.

Each closure member is adapted to carry within its socket, one or more beauty requisites or accessories, or to carry a container for such accessories as the case may be, or as desired by the user of the compact. As shown in the drawings, such beauty aids or accessories comprise the following items,

Member 4 carries a small container 8 of face powder which may be of the usual form having a rotating tip 9, to either retain or release the powder, according to the rotative position of said top.

Member 5 carries a tubular extension 10 and this extension, in turn, carries a reversible sleeve 11 in one end of which is inserted one end of a lip-stick 12, and in the other end of said sleeve is inserted one end of an eye-brow pencil 13. See Figs. 8 and 9.

Member 6 carries a cylindrical structure 14 which is centrally, longitudinally severed, so as to form two semi-cylindrical pans 15 and 16 which are hinged together at 17 and may be opened to the position shown in Fig. 12; when this device 14 is closed, and one end of it inserted within said member 6, it is firmly secured in the

closed position. The pan 16 may contain rouge and the pan 15 may contain mascara, each in a paste form, or any other accessories in paste form. The closure member 7 is shown as carrying a tubular extension 18, which, in turn carries an eye-brow brush 19. See Figs. 13, 14 and 15. Said Fig. 15 shows the sample "refill" which may be readily substituted in the place of one that has become worn.

As shown in the drawings said barrels are secured together by means of the metallic casing 1 but any other method of attachment may be employed, or the case may be an integral structure, and would preferably be such, if formed of bakelite or like material.

Attention is hereby directed to Letters Patent of the United States, No. 1,520,895, issued to me on the 30th day of December, 1924, for shoppers' nail cleaning and polishing sets to which this invention is intended to form a companion piece.

I claim the following:

1. In a beauty compact, the combination of a casing having formed therein a plurality of tubular parallel barrels, each barrel being open at both ends, a closure for each open end of the barrels, each closure comprising a flanged head and an inwardly

extended flange to fit in the bore of the barrel, a beauty aid receptacle fitted in and supported by each inwardly extended flange whereby to house beauty aids within the barrels.

2. In a beauty compact, the combination of a casing having formed therein a plurality of tubular parallel barrels, each barrel being open at both ends, a closure member for each opposite end of the barrels, each closure member having an inwardly facing socket to engage in the respective open ends of the barrels, and each socket member bearing a receptacle for beauty aids adapted to be partially and removably inserted within the respective receptacles and housed in the barrels.

3. In a beauty compact, the combination of a casing open at both ends and formed with a central reduced portion, a pair of barrels open at both ends and housed within the casing and confined in place by the central reduced portion, a closure for each open end of the barrels, said closures provided with sockets to support beauty aids to be partially and removably inserted within said sockets so as to be carried by said closure members.

In testimony whereof I affix my signature.
EDNA SIBLEY TIPTON.
